UNITED STATES PATENT OFFICE.

GEORGE R. HENDERSON, OF PHILADELPHIA, PENNSYLVANIA, ASSIGNOR TO THE BALDWIN LOCOMOTIVE WORKS, OF PHILADELPHIA, PENNSYLVANIA, A CORPORATION OF PENNSYLVANIA.

LOCOMOTIVE.

1,100,563.

Specification of Letters Patent. Patented June 16, 1914.

Application filed December 11, 1913. Serial No. 806,004.

To all whom it may concern:

Be it known that I, GEORGE R. HENDERSON, a citizen of the United States, residing in Philadelphia, Pennsylvania, have invented certain improvements in Locomotives, of which the following is a specification.

My invention relates to certain improvements in locomotives of the articulated type, *i. e.*, the type in which a number of frames support the boiler and, in the present instance, the tender. The frames are connected by joints so as to freely accommodate themselves to the curves of the track, the boiler having an articulated joint which will allow one section of the boiler to assume an angle with respect to the other section.

One object of my invention is to construct a locomotive of this type so that the two boiler sections will be independent, the steam from one section being used to drive half of the locomotive and the steam from the other section being used to drive the other half of the locomotive.

Another object of the invention is to make a quadruplex locomotive in which the boiler sections are rigidly mounted on two frames and are arranged to slide laterally on an intermediate frame, which may be termed a track, while the rear frame will support the tender.

A further object of the invention is to create a forced draft in the boiler tubes by means of a motor driven fan located in the smoke box of the boiler.

A still further object of the invention is to locate the engineer's cab at the forward end of the locomotive and the fireman's cab at the rear end of the boiler.

In the accompanying drawings: Figure 1 is a side view of my improved locomotive which is shown, in the present instance, as made in four sections, each section being independently driven. Fig. 2 is a plan view of Fig. 1, showing the locomotive as passing around a curve; Fig. 3 is a longitudinal sectional view of the forward end of the locomotive boiler; and Fig. 4 is a longitudinal sectional view of the rear end of the locomotive boiler.

Referring to the drawings, 1, 2, 3, and 4, in the present instance, are the four frames pivoted together by any suitable joints at 5 so that the frames will freely articulate as

the locomotive passes around a curve. In 55 the present instance, each frame has its own driving wheels 6, and mounted on the forward frame is a high pressure cylinder 7. The second frame has a low pressure cylinder 8 which receives steam from the high 60 pressure cylinder 7. On the third frame is a high pressure cylinder 9, and on the fourth frame is a low pressure cylinder 10, receiving steam from the cylinder 9. The boiler 11 of the locomotive, in the present 65 instance, is made in two sections 12 and 13. The forward section 12 of the boiler is rigidly mounted on the forward frame 1 and overhangs the second frame 2, and on this frame is a support 14 on which slides 70 the overhanging portion of the boiler. The rear section 13 of the boiler is rigidly supported on the third frame 3 and overhangs the second frame 2 and slides on the support 15 on the said second frame. The two 75 sections of the boiler are connected by a flexible joint 16 of the type fully set forth and claimed in the Patent No. 912,923, granted to S. M. Vauclain on the 13th day of February, 1909, so that while the sections, with their frames, are free to move independently, they are connected one to the other. In the rear section of the boiler is the fire box 17 and between the two sections is the secondary combustion chamber 80 16. At the forward end of the first section is the smoke box 18 having a stack 19.

20 are the rear tubes of the boiler secured to the tube sheets in the ordinary manner. These tubes are less in length than the fire 90 box 17 so that when it is necessary to remove the tubes they can be removed through the fire box, rendering it unnecessary to uncouple the two sections of the boiler when the rear tubes of the boiler have 95 to be repaired or replaced.

21 are the tubes of the forward section of the boiler mounted in suitable tube sheets. The rear tube sheet of this section forms the front wall of the secondary combustion 100 chamber, while the forward tube sheet forms the rear wall of the smoke box. The construction of the boiler is fully set forth and claimed in a companion application for patent filed by me December 11th, 1913, under 105 Serial No. 806,005.

The rear frame 4 supports the tender 22. At the fire box end of the boiler is the

cab 23 for the fireman and at the forward end of the locomotive is the cab 24 for the engineer, although the engineer may be located in the rear cab, if desired. By locating the engineer at the front of the locomotive, he has an unobstructed view, regardless of curves, smoke, or any leaks in the steam pipe, which would tend to blur his vision should he be located at the rear of the boiler. A speaking tube with proper whistles and indicators may be arranged so that orders can be transmitted from the engineer to the fireman, when necessary.

The two sections of the boiler are entirely independent as regards the steam space. There is no steam connection between the two sections of the boiler, but the products of combustion pass through the tubes of each section into the stack and these tubes may be of different sizes, as shown in the drawings, depending somewhat upon the character of the fuel used.

In order to create a sufficient draft in the boiler, I provide a fan 25, driven by a motor 26, in the present instance, of the steam turbine type, so as to cause a draft through the tubes, the fan delivering air to the stack, and I preferably arrange a diaphragm 27 directly back of the fan so as to cause all of the products of combustion to be drawn to the intake of the fan. I preferably mount the fan and the engine on rails 28 so that when the cap 29 at the end of the smoke box is removed, the motor and the fan can be withdrawn, and the diaphragm removed so that the tubes of the forward section can be withdrawn through the forward end of the section, although in some instances it may not be necessary to remove the diaphragm in order to remove the tubes that are in line with the opening therein. The steam turbine can be regulated by hand, or automatically, to maintain the necessary draft in the boiler.

I have not shown a superheater connected with any section, but superheaters of any suitable type may be used, if desired.

The sand box can be located at any suitable point on the locomotive and mechanical stokers, or other mechanism, may be used which may be essential to the operation of the locomotive, but which are not shown in order to avoid confusion.

It will be seen that each section of the boiler is comparatively short so that there will be less fluctuation in the height of water and less danger of exposing the crown sheet of the fire box when running down grade than if the boiler sections were connected by steam and water pipes. In fact, the variation of the water lever would be no greater than that of an ordinary locomotive. There are no articulated joints carrying either high or low pressure steam or injection water, as each section may be fed

by separate injectors obtaining water from the tender by means of hose connections in the ordinary way at the different points of articulation. Each section is provided with the ordinary safety valves.

30 is the throttle valve of the forward boiler section and the steam pipe 31 extends to the valve mechanism of the forward high pressure cylinders 7, while the exhaust from these cylinders will pass to the low pressure cylinders 8 through a pipe or receiver 32. The steam will exhaust from the low pressure cylinder through the pipe 33 to the atmosphere. The steam from the rear section of the boiler passes through the throttle valve 34, steam pipe 35, to the valve chamber of the high pressure cylinder 9, and from this cylinder through the pipe or receiver 36 to the valve chamber of the low pressure cylinder 10. The exhaust from this cylinder will pass through the pipe 37 to the exhaust pipe 28 at the rear of the tender to the atmosphere, or it may be used wholly, or in part, to heat the water in the tender. In some instances, where a second tender is used, it may be a driven tender and part of the steam from the high pressure cylinder may pass to the valve chamber of the low pressure cylinder 10 and part to the valve chamber of the low pressure cylinder on the frame of the second tender. This tender may be used where a greater capacity for coal and water is required. The rear tender, in this instance, may carry the water and the section next to the engine may carry the coal, if coal is used as the fuel.

By this construction, I obtain the maximum amount of tractive force generated by a single unit operated by a single crew with a minimum of dead weight. A further advantage of this construction is that the overhang of the boiler in passing around curves is very small, as each section of the boiler is comparatively short, and, consequently, the lateral displacement in passing around a curve is insignificant.

As remarked above, the water in the boiler of short sections will have less fluctuation in height. As one boiler section is entirely independent of the other with regards steam, there are no high pressure joints which are a constant annoyance in this type of locomotive.

The locomotive is operated by means of throttle and reverse levers located in the cab of the locomotive, as illustrated by dotted lines, Fig. 3, and connected to the rigging of the two engines, so that both valves will operate simultaneously. The same thing holds true with regards the power reverse gears. Each of these gears is arranged to operate the valve motion on the two articulated sections.

I claim:

1. The combination in a locomotive, of a

series of frames; a cylinder on each frame; driving wheels supporting the frames so that each frame is independently driven; a boiler made in two sections flexibly connected, the rear section and the forward section being rigidly secured to a frame and overhanging the intermediate frame.

2. The combination in a locomotive, of three frames; independent driving wheels for each frame and cylinders for each frame so that each frame is independently driven; and a boiler extending over the three frames and flexibly connected, the forward section of the boiler being rigidly mounted on the forward frame, the rear section being rigidly mounted on the rear frame, both sections overhanging the intermediate frame, said frame having slides for supporting the overhanging portion of the boiler.

20 3. The combination in a locomotive, of three frames; each frame having its own driving mechanism; a boiler extending over the three frames, said boiler being made in two sections flexibly connected, each section having an independent boiler section with flue tubes, the flue tubes being connected by an intermediate combustion chamber at the flexible joint; steam pipes leading from the front section of the boiler to the driving mechanism at the forward engine; and steam pipes connecting the rear section of the boiler with the driving mechanism of the rear frame, the driving mechanism of the intermediate section receiving steam from either one of the other driving mechanisms.

4. The combination in a locomotive, of four frames; driving wheels supporting each of said frames; a two-part boiler extending over three of the frames; a tender supported by the fourth frame; high pressure cylinders on the forward frame; high pressure cylinders on the third frame; low pressure cylinders on the second frame and low pressure cylinders on the fourth frame; a steam pipe leading from the forward section of the boiler to the high pressure cylinders on the first frame; a pipe leading from the exhaust side of the high pressure cylinders to the low pressure cylinders of the second frame; a steam pipe leading from the rear section of the boiler to the high pressure cylinders on the third frame; and a pipe connecting the exhaust side of said cyl-

inders with the low pressure cylinders of the rear frame carrying the tender.

5. The combination in a locomotive, of four frames; driving wheels supporting each of said frames; a two-part boiler extending over three of the frames; a tender supported by the fourth frame at the rear of the locomotive; high pressure cylinders on the forward frame; high pressure cylinders on the third frame; low pressure cylinders on the second frame; low pressure cylinders on the fourth frame; a steam pipe leading from the forward section of the boiler to the high pressure cylinders on the first frame; a pipe leading from the high pressure cylinders to the low pressure cylinders on the second frame; a steam pipe leading from the rear section of the boiler to the high pressure cylinders on the third frame; a pipe leading from the said last mentioned high pressure cylinders to the low pressure cylinders on the rear frame carrying the tender; an exhaust pipe leading from the low pressure cylinders on the second frame and an exhaust pipe leading from the low pressure cylinders on the rear frame; an engineer's cab at the front of the locomotive; a fireman's cab at the rear of the locomotive; and valve controlling mechanism in the cab at the forward end of the locomotive.

6. The combination in a locomotive, of a series of frames; independent driving mechanism for each frame; a boiler extending over three of said frames and a tender located above the fourth frame; said boiler having independent steam spaces; a fire box at one end of the boiler common to both steam spaces; a smoke box at the opposite end of the boiler; a stack; a fan for creating a draft through the boiler and communicating with the stack; and a motor for driving said fan, the exhaust from the cylinders of the driving mechanism being independent of the stack.

In testimony whereof, I have signed my name to this specification, in the presence of two subscribing witnesses.

GEORGE R. HENDERSON.
